UNITED STATES PATENT OFFICE.

ISIDOR MOSS, OF WALTHAM, MASSACHUSETTS.

ANTIFRICTION-BEARING.

SPECIFICATION forming part of Letters Patent No. 645,299, dated March 13, 1900.

Application filed November 8, 1899. Serial No. 736,237. (No model.)

To all whom it may concern:

Be it known that I, ISIDOR MOSS, a citizen of the United States, residing at Waltham, county of Middlesex, State of Massachusetts, have invented an Improvement in Antifric-
5 tion-Bearings, of which the following description, in connection with the accompanying drawings, is a specification, like letters and figures on the drawings representing like parts.

10 This invention relates to an antifric-
tion-bearing; and the object of the invention is to provide an improved device of this character which is simple in construction, easy run-
ning, and wherein the friction between the
15 several engaging parts is reduced to the smallest possible extent, thereby increasing the life of the bearing.

In the drawings, Figure 1 is a longitudinal
20 sectional elevation of an antifric-
tion-bearing constructed in accordance with my invention in the preferred embodiment thereof. Fig. 2 is a transverse section taken in the line 2 2, Fig. 1. Fig. 3 is a similar view, the section being taken in the line 3 3 on said Fig. 1. Fig.
25 4 is a view of the shaft, a roller, and sepa-
rator laid out flat. Fig. 5 is a view corre-
sponding to Fig. 1, showing one end only of a modified type of bearing. Fig. 6 is a trans-
verse section in the line 6 6, Fig. 5; and Fig.
30 7 is a detail in perspective of one-half of the roller-separator support.

The antifric-
tion-bearing illustrated in-
cludes a shaft or analogous support and a casing surrounding the same and a series of
35 rollers, the working portions of which are adapted to run against the shaft and the cas-
ing, respectively, and either of the last-men-
tioned parts may be rotative, although I am
enabled to secure a very important advan-
40 tage by rotating the casing or barrel. (Illus-
trated in Figs. 1, 2, and 3.) Referring now to
said figures, the shaft illustrated therein is denoted by S, and the casing or barrel sur-
rounding the same and inclosing or housing
45 the several rollers and their parts is denoted by C, and both of these may be, except as hereinafter specified, of any suitable kind. The shaft or support S passes freely through substantially-central openings in the caps 12
50 and 12', having inturned flanges 13 and 13' screw-threaded within the opposite ends of the casing. The rollers, which travel in con-

tact, respectively, with the shaft and the cas-
ing are denoted by R, and each of them in-
cludes a comparatively-long shank or body 14,
55 provided at its ends with enlarged heads 15
and 15', the heads being separated from each
other and sustained by the annular shoulders
or enlargements 16 and 16' on said shaft and
situated within the casing C near the oppo-
60 site ends thereof. The heads also engage the
inner walls of the flanges 13 and 13', and the
axes of the rollers and separators and shaft
are in parallelism.

The rollers R are spaced or separated to
decrease the friction between the parts, and
for this purpose I have represented a series
of roller-separators A, each separator co-oper-
ating with the adjacent rollers, between which
it is placed.

70 Referring to Figs. 2 and 3, where the rollers
and their roller-separators are shown ar-
ranged, respectively, in circular form, it will
be seen that the axes of the separators are
disposed within a circle intersecting the axes
75 of the rollers, by reason of which the rollers
themselves serve as a means for preventing
the separators from being forced radially out-
ward, and for preventing inward movement
of said separators I have illustrated independ-
80 ent means, to be hereinafter more particu-
larly described.

85 The roller-separators A (shown in Fig. 1)
are somewhat longer than the rollers which
they space, and they are supported at a point
beyond the working faces of the rollers, such
support in the present case serving to prevent
the inward movement of said separators, the
outward movement being prevented by the co-
operating rollers.

90 The roller-separators A each include a body,
as 17, which, like those of the rollers, are cy-
lindrical. The bodies 17 of the separators are
provided with the reduced necks 20 and 20',
adapted to fit against and travel upon the in-
95 turned sleeves 22 and 22', extending inward
from the caps 12 and 12'. The working faces
of said annular sleeves 22 and 22' are con-
centric with the axis of the shaft, and said
shaft passes through the same. When the
100 casing C is rotated, the working faces of the
sleeves 22 and 22' will be moved in the same
direction and also in the same direction with
the rollers supported thereagainst, as is also

the case with the modified form of device hereinafter set forth, by reason of which the motion of the separators is aided, as would not be the case were the support stationary or 5 fixed.

I provide means for preventing endwise movement of the rollers and the roller-separators.

The bearing portions 16 and 16' of the shaft 10 are furnished upon their inner sides with the annular projections 40 and 40', the surfaces of which are rounded, as will be seen upon inspection of Figs. 1 and 4.

The conical annular projections 41 and 41' 15 upon the rollers R are adapted to coöperate with said annular projections 40 and 40', it being seen that the projections 41 and 41' are located between the projections 40 and 40', so that endwise movement of the rollers relative 20 to the shaft is not possible.

What is shown as the double-beveled faces of the projections 41 and 41' bear in contact with the rounded faces of the projections 40 and 40' at a point in line with the plane of 25 contact between the shaft and the rollers and at the same radial distance from the axis of said shaft as said plane of contact, so that the friction at this place is materially reduced over that kind of a bearing having two annular shoulders or tongues whose point of engagement is at one side of such a plane.

The separators A are provided with annular projections 42 and 42', the outer faces of which are rounded and which bear against the inner 30 sloping faces of the conical projections 41 and 41' at points in line with the plane of contact between said separators and rollers, as clearly shown in Fig. 4, by reason of which the advantageous result just mentioned is secured 40 between the rollers and their separators.

The construction of the rollers and the intermediate separators shown in Figs. 4 to 6, inclusive, is the same as that represented in the preceding views, and hence I denote 45 the corresponding parts with the same reference characters, and in addition to this I will now proceed to describe the different embodiments.

Each of the heads 15 of the rollers R is provided with an outwardly-disposed central projection 30, and the latter have enlarged heads 31, adapted to travel against the inner faces of the annular inturned flanges or runways 33 of the cages B, the latter having central 55 openings 34, through which the shafts passes. The opposite ends of the roller-separators A roll upon the inner faces of the annular flanges 35, concentric with the first-mentioned annular flanges and surrounding the openings 34. 60 The flanges 35 are located inside the flanges 33. When the rollers are rotated, the heads 31, by engaging the inner surfaces of the flanges 33, cause the cages B to rotate, whereby 65 the outer faces of the inner flanges 35 will be caused to roll under the roller-separators, and thereby aid the movement of said separators and not act as a resistance to the free motion

thereof, as is the case in existing bearings of this type. The flanges 33 have inturned flanges 36, which engage the heads 31, so as to 70 prevent endwise movement of the roller-separators.

I have only represented a portion or half of the modified form of device, but have described the entire construction, using the different terms in the plural where generally only one is seen.

The invention is not limited to the precise parts previously set forth, for these may be variously modified within the scope of the accompanying claims.

Having fully described my invention, what I claim as new, and desire to secure by Letters Patent, is—

1. An antifriction - bearing comprising a 85 shaft, a casing, a series of rollers bearing against the shaft and casing, roller-separators between the rollers, and the axes of the same being within a circle intersecting the axes of the rollers, and each two of the latter serving 90 to hold the intermediate separator against outward movement, and independent means to hold said separators against inward movement.

2. An antifriction - bearing comprising a 95 shaft, a casing, a series of rollers bearing against the shaft and casing, roller-separators between the rollers, and the axes of the same being within a circle intersecting the axes of the rollers, and each two of the latter 100 serving to hold the intermediate separator against outward movement, and independent means rotative with the casing to hold said separators against inward movement.

3. An antifriction - bearing comprising a 105 shaft, a casing, a series of rollers bearing against the shaft and casing, the roller-separators, between the rollers, and the axes of the same being within a circle intersecting the axes of the rollers, and each two of the latter 110 serving to hold the intermediate separator against outward movement, and caps fitted within the casing, to support said separators and to hold the same against inward movement.

4. An antifriction - bearing comprising a 115 shaft, a casing, a series of rollers bearing against the shaft and casing, roller-separators between the rollers, and the axes of the same being within a circle intersecting the 120 axes of the rollers, and each two of the latter serving to hold the intermediate separator against outward movement, caps fitted within the casing provided with annular sleeves through which said shaft passes and which 125 support the ends of the separators.

5. An antifriction - bearing comprising a casing and a shaft, the rollers bearing against the shaft and casing, roller-separators for the rollers, projections upon the rollers and shaft touching at points in line with the planes of contact between the rollers and the shaft and such points and planes of contact being the same radial distance from the axis of the

shaft, and means operative with the casing to support the roller-separators.

6. An antifriction - bearing comprising a casing, a shaft extending into said casing, a 5 series of rollers mounted for movement upon the shaft, projections upon the rollers and shaft touching at points in line with the planes of contact between the rollers and the shaft and such points and planes of contact 10 being the same radial distance from the axis of the shaft.

7. An antifriction - bearing comprising a casing, a shaft extending into said casing, a 15 series of rollers mounted for movement upon the shaft, projections upon the rollers and shaft touching at points in line with the planes of contact between the rollers and the shaft, and roller-separators engaging the rollers and having projections in contact with 20 those of the rollers at points in line with the planes of contact between said rollers and roller-separators.

8. An antifriction - bearing comprising a casing, a shaft, a series of rollers mounted

for movement upon the shaft, projections 25 upon the rollers and shaft, the projections of one of said series of parts having rounded faces, while the faces upon the other series of parts are beveled upon straight lines, and the series of projections upon the rollers being 30 adapted to bear against those upon the shaft, at points in line with the planes of contact between the rollers and shaft.

9. An antifriction - bearing comprising a shaft, a casing, a series of rollers bearing 35 against the shaft and casing, roller-separators between the rollers, the rollers serving to hold the intermediate separators against movement in one direction, and independent means to hold said roller-separators against 40 movement in the opposite direction.

In testimony whereof I have signed my name to this specification in the presence of two subscribing witnesses.

ISIDOR MOSS.
